UNITED STATES PATENT OFFICE.

JOHN KARMAZIN, OF DETROIT, MICHIGAN.

RADIATOR AND METHOD OF FORMING THE SAME.

Application filed March 9, 1926. Serial No. 93,420.

This invention relates to radiators and more especially to the method and means for connecting the terminals of the water passages of the radiator within the water supply tank or to the outlet from the radiator. The invention is applicable, for example, to radiators of the general type described in my copending application. Serial No. 641,850, filed May 28, 1923, also though in its broader aspects not limited to this particular type of radiator.

One of the objects of the invention is to provide a simple, easy method of securing a tank to the core of a radiator of this type, whereby each water conduit will be connected to the tank without danger of closing or stoppage of any of the water conduits.

Another object of the invention is to provide a method of securing a tank to the core of a radiator whereby each conduit is connected to the tank without solder, it being necessary to solder only around the outer edges of the tank and core.

Another object of the invention is to provide a simple method of securing a tank to a radiator core in which each water conduit is considerably strengthened adjacent to the tank and the whole structure thereby rendered more rigid and firm.

Another object of the invention is to provide a radiator in which the upper and lower header sheets are held between the core and extra elements adapted to telescope with the water tubes of the core whereby the strength of the connection is dependent upon the strength of the extra or core element rather than upon a solder connection.

Other objects of the invention will be apparent as the description proceeds.

One embodiment of the invention has been illustrated in the accompanying drawings, in which Fig. 1 is a side elevation partly in section showing an upper tank wall, the parts in position before pressing together to form the rigid connection; Fig. 2 is a view corresponding to Fig. 1, but with the parts pressed securely together; Fig. 3 is an elevational view partly in section of the connection between the lower tank and the core.

For purposes of illustration, I have shown in the drawings a radiator core 10 comprising a plurality of superposed fins or elements 11 having integral tubular projections 12 telescoped together to form water

conduits 13 from top to bottom of the radiator core.

The upper water tank or header 14 has a bottom or header sheet 15 which is perforated in a plurality of places as at 16 to register with the water conduits 13 in the core.

An element 17 preferably identical with the elements 11 is adapted to fit inside of the tank 14, with tubular projections 18 thereon adapted to telescope into the projections 12 on the elements 11.

To secure the tank to the core the tank is laid upon the uppermost element 11 with the holes 16 registering with the water conduits 13 of the core. The element 17 is then placed over the bottom or header sheet 15 so that the projections 18 protrude through the holes 16 in the header 15 and enter the water conduits 13 in the core. The element 17 is then pressed firmly down as far as possible, forcing the projections 18 into the conduits 13, where they are held by friction securing the header sheet 15 firmly between the strip 17 and the uppermost element 11 of the core 10. A water tight connection is formed thereby between the telescoping projections 18 and the water conduits 13 so that the conduits 13 are, so to speak, extended up through the strip 17 and the holes 16 in the header sheet are closed and frictionally sealed by projections 18 passing therethrough.

If care is taken to provide the holes 16 of the proper diameter to fit snugly about the projections 18, the connection between the core and the tank may be made water tight without soldering, but to guard against the possibility of a leak due to unevenness in the projections 18 or size of the holes 16, solder may be applied to the outer edges of the header sheet 15 and the upper core element 11, as indicated at 19.

The lower tank 20 is secured to the core 10 in a similar manner as to the upper tank. The header sheet 21 is provided with holes 22 adapted to register with the water conduits 13 and receive the ends of the projections 12 on the lowermost element 11. The strip or extra element 23 has projections 24 thereon adapted to telescope with the projections 12 of the lowermost element 11 and is adapted to fit inside the tank 20.

The core 10 is set upon the bottom tank 20 with the projections 12 of the lowermost element protruding through the holes 22.

The strip 23 is then pressed up against the header sheet 21 as far as possible so that the projections 24 telescope with and frictionally engage the projections 12 of the 5 lowermost element of the core. A liquid tight connection is thereby made between the projections 12 of the lowermost strip and the projections 24 of the strip 23, and the holes 22 are sealed by the projections 12 of 10 the lowermost element of the core. This provides a liquid tight connection between the tank and the core but as in the case of the upper tank solder is applied around the edge of the lowermost element 11 of the 15 core and the header sheet 21 as at 25 to remove all possibility of leakage.

The projections 24 on the strip 23 may be shorter than the projections 12 on the elements 11 so as not to extend too far down 20 into the tank 20, or, if desired, certain of the conduits, as 26, may be cut off just below the strip 23 to provide an outlet for any steam which might collect in the lower tank beneath the strip 23, as described in 25 my issued Patent, No. 1,527,736, granted February 24, 1925.

With this construction, not only is a liquid tight connection provided, but at the same time the ends of the water conduits and the 30 header connections are greatly strengthened as the extra thickness of the projections of the strips 17 and 23 is added to that of the water conduits, making substantially double walled projections just below and above the 35 upper and lower headers, as shown for example in the sectional portions of Figs. 2 and 3. The ends of the water conduits merely frictionally engage the tubular projections on the strips, no solder being used, 40 and hence danger of clogging or closing any of the conduits is eliminated.

It will be understood that although I have illustrated one type of radiator core the invention in its broader aspects may be used 45 with any radiator core having a plurality of straight parallel inlets or outlets at an end thereof, and I do not therefore desire to limit my invention to the particular embodiment shown in the drawings but to interpret the invention broadly within the scope 50 of the appended claims.

I claim:

1. The method of attaching a water tank to a radiator core having water conduits 55 therein which comprises providing a member having a plurality of tubular projections thereon adapted to register with the water conduits of said radiator core, providing a tank having a wall with openings therein adapted to register with the water conduits 60 of said core, pressing said member against said core with the wall of said tank therebetween whereby said tubular projections frictionally engage with the water conduits 65 of said core and hold said tank and said core

together and soldering the outside edges of said core and said tank.

2. The method of attaching a water tank to a radiator core having water conduits 70 therein which comprises, providing a strip of metal adapted to fit inside said tank and having a plurality of tubular projections thereon adapted to simultaneously register with the water conduits in said core, providing the wall of said tank adjacent said core 75 with a plurality of openings adapted to register with the water conduits in said core, pressing said strip toward said core with the wall of said tank therebetween, whereby said tubular projections frictionally engage with 80 said water conduits to hold said tank and said core together and soldering together the outer edges of said tank and said core.

3. The method of attaching the core of a radiator having water conduits therein to a 85 water tank which comprises providing a strip of metal adapted to fit inside of the water tank and having integral tubular projections thereon adapted to register with the water conduits of said radiator core, providing one 90 wall of said tank with perforations adapted to register with said water conduits in said core, pressing said strip against said core with said perforated wall therebetween whereby said tubular projections are forced 95 into said water conduits to frictionally engage said conduits, whereby said tank is held firmly against said core, and soldering said core and tank together around the edges thereof. 100

4. The method of attaching a radiator core with water conduits therein to a water tank which comprises providing a strip of metal adapted to fit inside said tank, and having a plurality of integral tubular projections 105 thereon adapted to register with the water conduits of said core, providing one wall of said tank with perforations adapted to register with the water conduits in said core, pressing said strip against said core with 110 said perforated wall therebetween, whereby said tubular projections are simultaneously telescoped with the ends of said water conduits and said core is held rigidly against said tank and soldering together the edges of 115 said core and said tank.

5. The method of attaching a tank to the core of a radiator with water conduits therein a plurality of superposed fins having tubular projections thereon, said projections being in telescoping relation with each other 120 to form water conduits through said core, which method comprises providing an extra fin similar to the fins in said core, providing a plurality of openings in one wall of 125 said tank to register with said water conduits, pressing the projections of said extra fin into engagement with the outer fin of said core with said wall therebetween, whereby said water conduits in said core friction- 130

ally engage the tubular projections on said extra fin and hold said fin against the wall of said tank and said tank against said core, and soldering together the outer edges of 5 said tank and the adjacent fins of said core.

6. The method of securing a tank to the core of a radiator which comprises providing a member having a plurality of integral tubular projections thereon adapted to telescope with the water conduits of said core, providing one wall of said tank with holes adapted to register with the water conduits of said core, and pressing said member against said core with said wall therebetween 10 whereby said wall is firmly secured to said core.

7. The method of attaching a header to the core of an integral fin and tube type radiator, which comprises mounting a perforated wall of the header between two of the fin elements and moving said elements into contact with each side of said wall, with the projections of one element extending through said perforations and into the projections of the other element.

8. The method of securing upper and lower water tanks to the core of a radiator having water conduits therein which comprises the steps of providing a plurality of 30 holes in the bottom of said upper tank, adapted to register with the water conduits in said core, providing a plurality of holes in the top of said lower tank adapted to register with said water conduits, providing 35 a pair of strips having a plurality of tubular projections thereon adapted to register with the said water conduits and to fit one in each of said tanks, placing one of said strips in said upper tank with said projections 40 projecting downwardly through said holes, placing said tank and element upon said core with said projections inserted in said water conduits, placing the other of said strips in said lower tank with said projections 45 registering with said holes, placing said core upon said lower tank with said water conduits protruding through said holes and into the tubular projections on said strip, pressing said strips firmly toward 50 said core whereby said upper and lower tanks are held firmly against said core with the adjacent walls of said tanks held between said strips and said core and soldering said core and tanks together 55 around the outer edges thereof.

9. A radiator comprising a core having a plurality of water conduits passing therethrough, an upper water tank having a plurality of holes in the bottom thereof adapted to register with said water conduits, a strip 60 having tubular projections thereon projecting through the holes in the bottom of said tank and frictionally engaging with said water conduits, a lower water tank having a plurality of holes in the top thereof 65 adapted to register with said water conduits and through which the ends of said water conduits project, a strip having tubular projections thereon adapted to register and frictionally engage with the ends of 70 said water conduits whereby the bottom and top of said upper and lower tanks respectively are held firmly connected to said core.

10. A radiator comprising a core having a plurality of water conduits, an upper tank 75 having a plurality of holes in the bottom thereof adapted to register with said water conduits, a lower tank having a plurality of holes in the top thereof adapted to register with said water conduits, a strip in each 80 of said tanks having a plurality of tubular projections thereon adapted to register with and frictionally engage said water conduits whereby each of said conduits is connected to said upper and lower tanks and said tanks 85 are firmly attached to said core.

11. A radiator comprising a core consisting of a plurality of fin elements having integral tubular projections extending therefrom with the projections of one element 90 extending into the projections of the adjacent element to form water conduits through the core, and header tanks having one wall thereof mounted between the two fin elements at each end of the core. 95

12. In a radiator, a core constructed to permit water flow therein, a plurality of terminal water passages at its end, a header member covering said core end and provided with holes registering with the ends of said 100 passages, and a plate on the opposite side of said header member having tubular projections registering with said terminal passages and said plate member perforations, said tubular projections being integrally 105 connected, and said connecting portions additionally reinforcing said header member.

In testimony whereof I have affixed my signature to this specification.

JOHN KARMAZIN.
